(57) **CLAIM**

The ornamental design for an abrasive wheel, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of an abrasive wheel.

FIG. 2 is a front elevation view of the abrasive wheel of FIG. 1.

FIG. 3 is a rear elevation view of the abrasive wheel of FIG. 1.

FIG. 4 is a left plan view of the abrasive wheel of FIG. 1.

FIG. 5 is a right plan view of the abrasive wheel of FIG. 1.

FIG. 6 is a top plan view of the abrasive wheel of FIG. 1.

FIG. 7 is a bottom plan view of the abrasive wheel of FIG. 1.

FIG. 8 is a bottom perspective view of the abrasive wheel of FIG. 1.

FIG. 9 is a front perspective view of a second embodiment of an abrasive wheel.

FIG. 10 is a front elevation view of the abrasive wheel of FIG. 9.

FIG. 11 is a rear elevation view of the abrasive wheel of FIG. 9.

FIG. 12 is a left plan view of the abrasive wheel of FIG. 9.

FIG. 13 is a right plan view of the abrasive wheel of FIG. 9.

FIG. 14 is a top plan view of the abrasive wheel of FIG. 9.

FIG. 15 is a bottom plan view of the abrasive wheel of FIG. 9.

FIG. 16 is a bottom perspective view of the abrasive wheel of FIG. 9.

FIG. 17 is a front perspective view of a third embodiment of an abrasive wheel.

FIG. 18 is a front elevation view of the abrasive wheel of FIG. 17.

(Continued)

FIG. 19 is a rear elevation view of the abrasive wheel of FIG. 17.
 FIG. 20 is a left plan view of the abrasive wheel of FIG. 17.
 FIG. 21 is a right plan view of the abrasive wheel of FIG. 17.
 FIG. 22 is a top plan view of the abrasive wheel of FIG. 17.
 FIG. 23 is a bottom plan view of the abrasive wheel of FIG. 17.
 FIG. 24 is a bottom perspective view of the abrasive wheel of FIG. 17.
 FIG. 25 is a front perspective view of a fourth embodiment of an abrasive wheel.
 FIG. 26 is a front elevation view of the abrasive wheel of FIG. 25.
 FIG. 27 is a rear elevation view of the abrasive wheel of FIG. 25.
 FIG. 28 is a left plan view of the abrasive wheel of FIG. 25.
 FIG. 29 is a right plan view of the abrasive wheel of FIG. 25.
 FIG. 30 is a top plan view of the abrasive wheel of FIG. 25.
 FIG. 31 is a bottom plan view of the abrasive wheel of FIG. 25; and,
 FIG. 32 is a bottom perspective view of the abrasive wheel of FIG. 25.
 The broken lines show portions of an abrasive wheel that form no part of the claimed design.
